UNITED STATES PATENT OFFICE.

WILLIAM H. SPENCER, OF BOGOTA, NEW JERSEY, ASSIGNOR TO I. P. FRINK INC., OF NEW YORK, N. Y., A CORPORATION OF NEW YORK.

LAMP FIXTURE.

Application filed March 4, 1926. Serial No. 92,260.

This invention relates more especially to lamp fixtures in which the completely finished parts and sections which go to make up the whole, may be assembled or dismantled at will.

The primary object of my invention is to provide an improved construction combination and arrangement of parts in a lamp fixture of this character whereby the number 10 of parts and sections of different kinds, may be reduced to a minimum so as to enable it to be more economically constructed, more expeditiously assembled and whereby the transportation of such fixtures may be 15 greatly facilitated without sacrificing its utilitarian or ornamental qualities.

Toward the attainment of these objects, my invention contemplates an improved organization of parts and improved adjustable connections therefor to provide an improved interchangeability of said parts, to facilitate their replacement, and withal, to increase their variable relationships.

One of the objects of my invention is to 25 provide an improved connection head for variably and releasably uniting the frame-members or bracket arms of a lamp fixture.

Specific objects of invention will appear in the specification and be pointed out in the 30 appended claims in connection with the accompanying drawings which illustrate certain preferred adaptations of my invention.

In the drawings,

Figure 1 is a side elevation of a suspension lamp constructed in accordance with the 35 principles of the present invention;

Figure 2 is an enlarged vertical section of the lower part of Figure 1, parts being 40 broken away and parts shown in elevation;

Figure 3 is an enlarged perspective view of the separated parts of the upper connection-head detached;

Figure 4 is an enlarged vertical section of the lower connection-head, parts being 45 shown in elevation;

Figure 5 is a section on the line 5—5, Figure 4;

Figure 6 is an enlarged perspective view 50 of the separated parts of the lower connection-head.

Figure 7 is a fragmentary plan view showing the method of stamping frame members from sheet metal;

Figure 8 is a side elevation of another 55 embodiment of my invention;

Figure 9 is a side elevation of another embodiment of my invention;

Figure 10 is a detail of a modified form of frame-member.

Referring to the embodiment of my invention shown in Figures 1, 2, 3, 4, 5, and 6 of the drawings, a depending eye-bolt 1 serves as an anchorage for a chain 2 from which is suspended an eye-bolt 3. The eye-bolt 3 is provided with screw threads, a lamp socket 4 being threaded thereto for the reception of a lamp 4^a. Carried by the shank of eye-bolt 3 and arranged above the lamp socket 4 is an annular block or cylinder shown in detail in Figure 3, said cylinder being provided 60 with radial slots 5 opening thru one end thereof and extending to an unslotted annular end portion 6 at the other end thereof. Extending axially thru said slotted block, and closing the inner ends of said radial 65 slots, is a thimble 7 having a bore which fits the shank of said eye-bolt, said thimble being provided with a reduced upper end 8 for rotatably mounting a cap 9. The cap 9 is provided with a depending peripheral 70 flange 10 which extends across the upper ends of the peripheral openings formed by the radial slots 5 in the annular block. The flange 10 is provided with a notch 11 which may be moved into register with any one of 75 said peripheral openings in the slotted block so as to admit one end of a bracket arm or frame-member to be presently described. The slotted cylinder, rotary cap 9, and thimble 7 constitute the upper connection-head, 80 a ring nut 12 being threaded to the lower end of the stud 3 for retaining said connection-head in position on the eye-bolt. As shown in Figures 1, 2 and 4, the lamp frame 85 includes frame-members 13 which have their upper ends interlocked with the upper connection-head, and their lower ends interlocked with a lower connection-head of somewhat similar construction. Said lower connection-head, the separated parts of which 90 are shown in perspective in Figure 6, comprises an annular block or cylinder 14 provided with radial slots 15 in one end thereof, a bottom cap 16 with an upwardly presented 95 peripheral flange 17, and a split-washer 18 which is interposed between said bottom cap 16 and an annular enlargement 19 of a stud bolt 20. Said stud bolt 20 is provided with 100 a reduced end 21 which is threaded into the annular unslotted portion 14^a of the slotted 105 cap 16. Said stud bolt 20 is provided with a reduced end 21 which is threaded into the annular unslotted portion 14^a of the slotted 110 cap 16.

block 14. It will be seen from this description that after the stud bolt 20 has been screwed home into the slotted block 14, the split washer 18 exerts a yieldable pressure upon the cap 16 to yieldably retain it in adjusted position while permitting it to be adjusted on its axis to bring a notch 22 in the peripheral flange 17 of cap 16 into register with any one of the slots 15. In this position of the cap, a frame-member may be inserted or removed as the case may be.

As shown in Figure 7, the frame-members 13 may be economically constructed by cutting them from sheet-metal. According to 16 this embodiment of my invention, each frame-member 13 is provided at its upper end with an upwardly-presented lug 23 which interlocks with the peripheral flange 10 of cap 9 as soon as notch 22 is shifted by 20 the movement of said cap. At the same time, the upper end of frame-member 13 may be provided with a rounded corner 24 to permit the lug 23 to be inserted behind the flange 10 without bringing the notch 22 into 25 register with the slot 15, each frame-member 13 having its lower end provided with a downwardly-presented lug 25 which may be swung into position to be locked behind the flange 17 of lower cap 16.

30 In the embodiment of my invention shown in Figure 8, a fixture support in the form of a standard 26 is provided with a connection-head 27 of substantially similar construction to one or the other of those described above. 35 Interlocked with the connection-head at their lower ends, are oppositely-presented frame-members 28 which serve to mount a shade 29.

According to the embodiment of my invention shown in Figure 9, a depending chain 30 is connected to an eye-bolt 31 which has its lower end threaded into a lamp socket 32. Arranged above the lamp socket 32, is a slotted connection-head 33 with 45 which are interlocked the upper ends of frame-members 34, the lower ends of said frame-members being interlocked with a lower connection-head 35. In this adaptation of my invention, the side frames are 50 suitably formed to represent a swinging lantern.

According to Figure 10, my invention contemplates the employment of frame-members 55 which are mounted at one end only so as to serve as bracket arms which may be presented upwardly or downwardly from a connection-head.

In the embodiment of my invention shown in Figure 10, bracket arms 36 are interlocked 60 at their upper ends in a connection-head similarly constructed to that shown in Figure 3. For this purpose, the bracket arms 36 are provided at their upper ends with rectangular projections 37 which are adapted 65 to fit into the radial slots 38, the flat facets

39 on the under sides of projections 37 resting upon the bottom walls of said radial slots. Inwardly presented shoulders 40 on the bracket arms 36, abut against the outer periphery of the unslotted annular portion 70 41 of the slotted block. Opposite the facet 39, each bracket arm is provided with an upwardly-presented lug 42 which is formed by a notch 43, said notch receiving the downwardly-presented flange 44 of rotary cap 75 45 and thus interlocking with lug 42. If desired, the outer ends of bracket arms 36 may be provided with holes 46 to facilitate the attachment of ornamental and utilitarian accessories (not shown).

80 I claim:—

1. In a lamp fixture, the combination with a connection head comprising a bracket-arm supporting block and a cap rotatable in a fixed plane on said block, said block being provided with a recess opening axially and radially outward, and a bracket-arm having one end seated in said recess and provided with a projection presented toward said cap, said cap having an axially-presented flange 90 adapted to interlock with said projection, said flange being provided with a notch movable into and out of position to permit the passage of said projection into and out of position behind said flange.

2. In a lamp fixture, the combination with a connection head having a radially-opening bracket-arm recess provided with an inwardly-presented shoulder adjacent to the mouth of said recess, of a second connection head axially spaced therefrom and comprising relatively rotatable portions in fixed axial relation to each other said portions being provided with notches movable into and out of registry, and a bracket-arm having axially-presented lugs at opposite ends thereof, one end of said bracket-arm being provided with a rounded corner permitting the insertion of said lug into lateral abutment with said shoulder by an angular movement thereon, the other end of said bracket-arm being movable laterally thru said registered notches in said second connection head.

105 3. In a lamp fixture, the combination with a connection head with an outwardly-opening bracket-arm recess and an inwardly-presented shoulder adjacent to said recess, of a bracket-arm provided adjacent one end with a cross-section approximately filling said opening and with a projecting lug adapted to engage inwardly-presented shoulder, that end of said bracket arm being provided with a rounded corner opposite to the face of said lug presented to said shoulder whereby said end may be inserted into said recess by a swinging movement about said shoulder, a connection head for the other end of said bracket-arm, the last-mentioned connection head comprising a supporting 110 115 120 125 130

block provided with a notch and a cap rotatable thereon in a fixed plane, said cap having a notch movable into registry with the notch in said block to admit the other 5 end of said bracket-arm and out of registry therewith to lock said other end against displacement.

4. In a lamp fixture, the combination with a bracket-supporting block provided with 10 a slot in a flat end wall thereof, said slot having an opening at the outer edge of said block, a cap movably connected to said block and provided with a flange slidably contacting with said flat end wall, said 15 flange being provided with a notch movable into and out of register with said slot, and a bracket-arm having one end provided with a cross section substantially fitting the combined opening formed by said slot 20 and notch in register and with a reduced adjacent cross-section substantially fitting the opening corresponding to the slot alone said bracket-arm being locked in said block by said flange when said notch is moved out of 25 register with the slot therein.

5. In a lamp fixture, the combination with a cylindrical bracket-supporting block provided with radial slots opening radially thru the periphery of said block and axially 30 thru a flat end wall thereof, of a rotary cap coaxial with said block and having a circular flange slidably contacting with the slotted flat end wall of said block, said flange being provided with a notch movable 35 into and out of register with each of the slots in said block, and a bracket-arm provided at one end with a cross section substantially equal to the opening formed by one of said slots and said notch combined 40 and adjacent thereto with a cross-section substantially equal to the cross-sectional area of the slot alone.

6. In a lamp fixture, the combination with 45 axially-spaced cylindrical bracket-supporting blocks provided with radial slots opening radially thru the peripheries of said blocks and axially thru flat end walls thereof, of a rotary cap coaxially connected to each of said blocks and having a circular flange slidably contacting with the flat end 50 wall thereof and provided with a notch movable into and out of register with any one of said slots, and a bracket-arm having its opposite ends provided with cross-sections substantially fitting the openings formed by 55 said slots and notches when in register and with reduced cross-sections adjacent thereto substantially fitting the cross-sectional areas of the slots alone whereby said bracket-arm may be locked at opposite ends within 60 said blocks when said notches are moved out of register with said slots.

7. In a lamp fixture, the combination with 65 axially-spaced coaxially-arranged connection-heads, each of said connection-heads

having a bracket-arm recess provided with an outwardly-presented opening and an inwardly-presented shoulder adjacent to said opening, of a bracket-arm provided adjacent one end with a cross-section approximately 70 fitting the recess opening of one of said connection-heads and with a gradually reduced cross-section and having an outwardly-presented shoulder in abutment with said inwardly-presented shoulder, said bracket-arm 75 being adapted to be moved into and out of interlocking engagement with said connection-head at that end by a swinging movement about the latter, the other of said connection-heads being provided with a 80 swivelled cap having a flange interlocking with the other end of said bracket-arm and provided with a notch permitting the introduction and removal of that end.

8. In a lamp fixture, the combination with 85 axially-spaced coaxially-arranged connection heads, one of said connection-heads having a bracket-arm recess provided with an inwardly-presented shoulder and the other of said connection heads being provided with a 90 swivelled cap having a flange provided with a notch, of a bracket-arm provided adjacent one end with a cross-section approximately 95 fitting the recess opening of the first-mentioned connection head and with an upwardly 100 presented abutment adapted to interlock with said shoulder, said notch being adapted to permit the introduction and removal of the other end of said bracket-arm into and out of position to be engaged by said flange.

9. In a lamp fixture, the combination with 105 axially-spaced coaxially-arranged connection-heads, each of said connection-heads having a bracket-arm recess provided with an outwardly-presented opening and an inwardly-presented shoulder adjacent to said opening, of a bracket-arm provided at one end with an upwardly-presented abutment in contact with one end wall of the recess in said connection-head and bearing below 110 against the opposite end wall of said recess, that end of the bracket-arm being provided with a rounded corner extending between said abutment and the recess-opening to permit the interengagement of said bracket-arm with said connection-head by a swinging movement of the former about the latter, and means carried by the other of said connection heads for releasably locking the other end of said bracket-arm in position. 115

10. In a lamp fixture, the combination with 120 axially-spaced coaxially-arranged connection-heads, each of said connection-heads having a bracket-arm recess provided with end walls, an inner vertical wall, an outwardly-presented opening and an inwardly-presented shoulder adjacent to said opening, of a bracket-arm provided adjacent one end with a cross-section approximately 125 fitting the recess opening of one of said connection- 130

heads and with a gradually reduced cross-section terminating in an upwardly-presented abutment in contact with one end wall of the recess in said connection head, said bracket-arm being in endwise abutment with said inner vertical wall of the recess and having an outwardly-presented shoulder in abutment with said inwardly-presented

shoulder, the other of said connection heads being provided with a swivelled cap having a flange interlocking with the other end of said bracket-arm and provided with a notch permitting the introduction and removal of that end of the bracket-arm. 10

WILLIAM H. SPENCER.
